UNITED STATES PATENT OFFICE

109,831

DESIGN FOR A TEXTILE FABRIC OR SIMILAR ARTICLE

Leo Franklin, Cedarhurst, N. Y., assignor to Phoenix Manufacturing Co., Inc., New York,
N. Y.

Application April 29, 1938, Serial No. 76,841

Term of patent 3½ years

To all whom it may concern:

Be it known that I, Leo Franklin, a citizen of the United States, residing at Cedarhurst, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric or similar article as shown.

LEO FRANKLIN.
